UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ENGINE.

Application filed January 8, 1926. Serial No. 80,016.

This invention relates to fluid actuated engines, and more particularly to that type of engine in which there is provided a plurality of pistons, one of which is adapted to oscillate within the other piston as a cylinder. 5

It is an object of this invention to enable the pistons to be tightly sealed to prevent leakage of motive fluid past the bearing surfaces.

Other objects will be in part obvious and in part pointed out hereinafter.

In the drawings forming part of the specification and in which similar reference characters refer to similar parts,

Figure 1 is a vertical cross section taken along the line 1-1 looking in the direction of the arrows, of an engine constructed in accordance with the practice of the invention,

Figure 2 is a longitudinal section of the engine taken along the line 2-2 looking in the direction of arrows, and

Figure 3 is a vertical cross section of a modification of the engine.

Referring to the drawings, the engine illustrated comprises a cylinder A within which there is adapted to move an outer flat piston B. In the embodiment shown in Figures 1 and 2, the piston B is of the reciprocating type and is rectangular in cross section being adapted to slide between two wearing plates C at the top and bottom of the cylinder and also between two flat surfaced heads D and E at the front and back respectively of the cylinder A. The engine is therefore of the type known as a square piston engine and leakage is prevented by the closeness of the fit between the piston B and the heads D and E and wearing plates C. The piston B is actuated by motive fluid admitted and exhausted through ports F and G at either end of the cylinder A the distribution of such motive fluid being accomplished by means of a distributing valve of any suitable description, a preferred form being described hereinafter. Wholly within the piston B there is adapted to operate a second or inner piston H the motion of which preferably is not parallel to that of the piston B.

In accordance with this invention the piston H is adapted to oscillate within the outer piston B and to this end is provided with a cylindrical pivoted end J adapted to be in-

serted in a bearing K adjacent one end of the piston B while the other end of the piston H opposite the pivot is provided with an arcuate face L slideable along a face O of the piston B curved with its center of curvature 60 at the pivotal center of the cylindrical end J.

To perform useful work, the inner or oscillating piston J is pivotally mounted on a crank P extending into the cylinder A and attached to a crank shaft Q journaled as by 65 means of a bearing R in the back head E. It will be noted that as the outer piston B reciprocates and the inner piston H oscillates within the piston B the motion of the two pistons will be resolved through the crank 70 pin P into rotary motion in the crank shaft Q. Motive fluid for actuating the inner piston H is admitted into the cylinder A through ports S and T located at the sides of the piston B.

The crank shaft Q is preferably provided with a flanged end U the inner face of which is flushed with the inner face of the back head E for the purpose of providing a support for the crank pin P. The inner piston H is accordingly provided with suitable wings V extending from the main portion of the inner piston to prevent uncovering of the joint between the flange U of the crank shaft and the back head E and likewise an 85 aperture W in the front head D to prevent leakage to atmosphere of motive fluid within the outer piston B. In the embodiment shown in Figure 3 the engine is provided with a cylinder b in which the outer piston c is adapted to oscillate being pivoted at a bearing end d in a bearing e mounted in the cylinder b, the other end of the piston c being provided with an arcuate shaped portion f adapted to slide on a curved face g of the cylinder b. Motive fluid for actuating the piston f is admitted into the cylinder b at ports h and j to cause oscillation of the piston c about its pivoted end d. An inner piston k is likewise pivoted within the outer piston c being provided with a cylindrically formed end o mounted in a similarly shaped aperture p in the piston c and adapted to oscillate at right angles to the oscillatory movement of the piston c in an aperture q formed therein. The piston k is provided with an end r arcuate in form and sliding on a surface s similar in curvature within the piston c. Motive fluid for actuating the piston k is admitted to the space 100 110

g within the piston c through suitable ports t and u. The oscillatory movement of the pistons c and k are resolved into a rotary motion of the crank pin v the piston k being 5 suitably journaled thereon. As in the case of the engine shown in Figures 1 and 2 the inner piston k is provided with wings w to prevent leakage of motive fluid at the point where the crank shaft (not shown) enters 10 the cylinder b.

In both the above described embodiments of the invention, clearance between the pistons and the parts within which they operate is reduced to a minimum to prevent 15 loss of motive fluid for actuating the engine.

The valve for distributing the admission and exhaust of motive fluid to the cylinders A and b, as the case may be, may be of any suitable description. In this embodiment 20 the valve comprises a rotary cylindrical body member 2 adapted to be rotated by a pin 3 projecting into the cylinder head D and engaging the body portion 2 at an aperture 4. Suitable passages 5 are provided 25 leading to the ports F, G, S and T from a cylindrical bore 6 within which the valve body 2 is adapted to rotate.

The valve body 2 is provided with three 30 chambers 7, 8 and 9, circumferentially spaced apart and adapted to register with the passages 5 successively. The passage 9 is arranged to be always in communication with atmosphere through a port 10 and is always used for exhaust. The chambers 7 35 and 8 are adapted to be alternatively connected with a supply of motive fluid from a supply pipe 11 through a suitable throttle valve 12. If one of the passages 7 or 8 is connected with the supply of motive fluid 40 the other of said passages is arranged to be connected to the atmosphere for exhausting motive fluid from the cylinder A or b in the manner as substantially described in application, Serial No. 18,689, filed March 27, 45 1925.

The pistons within the cylinders A and b may be lubricated by oil carried thereto along with the air supplied through the pipe 11. To those parts which are not accessible 50 to the motive fluid, such as a crank pin 3,

oil may be supplied through a longitudinal passage 13 leading to a reservoir 14 for oil formed integrally with a cap or plug 15 at the end of the bore 6 and which acts additionally as a bearing for a broaching cylindrical end 16 of the valve body 2. 55

I claim:

1. A fluid actuated engine comprising a cylinder, a piston in the cylinder, a second piston pivotally mounted in said first piston 60 and adapted to oscillate therein, and a crank shaft attached to said second piston and adapted to be rotated thereby.

2. A fluid actuated engine comprising a cylinder, a crank shaft, an outer flat piston 65 in said cylinder, and an inner piston pivotally mounted wholly within said outer piston and connected to the crank of said crank shaft to transmit the motion of both of said pistons to said shaft. 70

3. A fluid actuated engine comprising a cylinder, a crank shaft, an outer flat piston in said cylinder, and an inner flat piston pivotally mounted to oscillate wholly within said outer piston and rotatably connected 75 with the crank of said crank shaft to transmit the motion of both of said pistons to said shaft.

4. A fluid actuated engine comprising a cylinder, a crank shaft having a crank extending into said cylinder, an outer piston pivotally mounted to oscillate in said cylinder, and an inner piston pivotally mounted in said outer piston to oscillate therein and attached to the crank of said shaft to transmit the oscillatory motions of both pistons to said shaft. 80 85

5. A fluid actuated engine comprising a cylinder, a shaft having a crank extending into said cylinder, an outer piston movable 90 in said cylinder, and an inner piston pivotally mounted wholly within said outer piston to oscillate therein and to transmit motion of both said pistons to said crank, said inner piston having an arcuate end opposite the pivot to cooperate with a surface of said outer piston. 95

In testimony whereof I have signed this specification.

CHARLES C. HANSEN.
